[57] CLAIM

The ornamental design for a wheel chock, as shown and described.

DESCRIPTION

FIG. 1 is a front perspective view of a wheel chock showing my new design.

FIG. 2 is a top plan view thereof.

FIG. 3 is front elevational view thereof, taken in the direction of arrow 3—3 in FIG. 2, with the rear elevational view being a mirror image of FIG. 3.

FIG. 4 is a left side elevational view thereof, taken in the direction of arrow 4—4 in FIG. 3.

FIG. 5 is a right side elevational view thereof, taken in the direction of arrow 5—5 in FIG. 3.

FIG. 6 is a bottom plan view thereof, taken in the direction of arrow 6—6 in FIG. 3; and,

FIG. 7 is a bottom plan view of an alternative embodiment of a wheel chock showing my new design.
